FOLDABLE IRONING BOARD

James J. Foglio, New Rochelle, N. Y.

Application October 23, 1946, Serial No. 705,078

6 Claims. (Cl. 38—139)

1

My invention relates to a foldable ironing board and has for its object to improve upon and to simplify the construction of ironing boards so that a strong, substantial and rigid support for the ironing operation is provided and the ironing board with its supporting legs may be folded together into a compact structure, convenient for packing into a valise or bag for use in travelling, and for convenient storage in a minimum of space at home.

A further object of my invention is to provide an ironing board of which the sections may be folded upon each other with the ironing pad innermost so that the pad will remain practically dustless during storage.

A further object of my invention is to provide a rigidly supported ironing board in which there is sufficient room between the supporting legs so that the person ironing may occupy a sitting position with his legs below the board.

A still further object of my invention is to provide a rigidly supported ironing board in which the supporting legs are adjustable in height to position the board at the best height for the particular user while the legs rest on the floor or on an elevated surface, such as a chair or table, and in which the board may be positioned level even though the floor or elevated surface is not level.

A still further object of my invention is to provide supporting legs for an ironing board so positioned that the legs provide a maximum clearance for work encircling one end of the board and extending lengthwise of the board.

A specific embodiment of my invention is shown in the accompanying drawings in which:

Fig. 1 is a side elevational view, partially in section, of my foldable ironing board collapsed for packing or storage;

Fig. 2 is a top view, partially broken away, of the board of my invention extended for use;

Fig. 3 is a side view of the board of my invention extended for use; and

Fig. 4 is an elevational view of the extensible legs employed in the ironing board of my invention.

Referring to the drawings, my ironing board is composed of two portions, 1 and 2, of which as is customary portion 1 has its free end more rounded than that of portion 2. The two portions have rectilinear opposed transverse edges in which are positioned a pair of bar-top hinges 18, pivotally connecting the portions to each other. Hinges 18 are placed inwardly from the lengthwise edges of both board portions and are flush with the upper surface thereof, which upper sur-

2

face is covered with the usual pad, not shown. A bayonet 19 is fastened to the bottom of board 1 and extends beyond the transverse edge of the board in the form of a slit 20. On the bottom surface of board 2, a threaded pin 21 is mounted in such location that when the boards are aligned in the working position, pin 21 falls within the slit 20 and extends below it. The wing nut 22 is threaded on pin 21 and after opening and aligning the boards 1 and 2 about the hinges 18, the nut 22 may manually be threaded down the pin onto bayonet 19, thus rigidly locking the boards to each other in the working and aligned position.

Preferably as close to bayonet 19 on the underside of board 1 as manufacturing ease will permit, an angle 11 is mounted centrally of the lengthwise edges of the board, the angle having an integral side member 12 extending parallel to such board edges. By pin 13, mounted in side member 12, the square cross-sectioned, upper leg 4 is pivotally connected to board 1. An eye 10 is carried by leg 4 and, in the folded position of leg 4, partially enters a convenient recess in the bottom of board 1 (Fig. 1). Leg 4 is adapted to enter a hollow leg 3, between the closed bottom of which and the lower end of leg 4 compression spring 5 tends to move legs 4 and 3 relative each other so that leg 4 is as far out of leg 3 as the spring can force it. The threaded angle bolt 6 mounted in the upper portion of leg 3 above the uppermost position of the lower end of leg 4 as determined by spring 5 as shown, or even still further up on the leg, serves to clamp the legs at any adjusted position. Hollow leg 3 is provided with a plurality of diagonally extending leg members 7 from the upper region of the leg outwardly and downwardly to connect with the cross member 23. The cross member 23 is so disposed as to extend transversely the board 1, thus resulting in a wider, steadier and almost non-tipping support; and to retain such disposition I make the legs 3 and 4 of square cross-section, but obviously any other shape which prevents rotation of sleeve 45 leg 3 about leg 4 is equally satisfactory.

Angle 11 is so mounted on board 1 that the vertically depending portion of such angle is nearest the edge about which board 1 is hinged. In folding the leg 4 pivoted thereto at 13, it is possible only so to pivot the leg that all of it lies below board 1, that is, in the counterclockwise direction in Fig. 3. Hence, when extending the leg to set up the board, it is necessary to provide a stop, in the form of removable pin 14, in side member 12. When pulling the leg from its folded

down position, pin 14 is removed from side member 12 and is restored after the leg has been pivoted beyond the hole in the side member for receiving the pin. To prevent the loss of pin 14, it may be attached by a chain or otherwise, not shown, to board 1. A hook attached to the bottom of the board is positioned so as to be engageable with eye 10 on leg 4, thereby holding leg 4 tightly against pin 14. In such hooked position, the leg assembly is so positioned that its cross member 23 is at a greater horizontal distance from the hinged edge of the board than pin 13, whether leg 4 is within or almost without hollow leg 3.

An identical leg assembly, comprising upper square leg 4, hollow square leg 3, spring 5, side leg members 7 and cross member 23, is pivoted at the upper end of leg 4 to angle 15 attached to the bottom surface of board 2. Angle 15 has a side member 16, parallel to the lengthwise edges of the board 2, in which pin 17 pivotally supports leg 4. The angle 15 is attached to board 2 at a distance from the free end of the board 2 which is approximately equal to the distance from the hinged end of the board 1 at which angle 11 is attached to that board. The vertically depending portion of angle 15 is such that the leg 4 attached thereto has but limited motion in the clockwise direction (Fig. 3). The leg assembly pivots under board 2 so that, providing leg 4 is as far in hollow leg 3 as it will go, no part of the leg assembly extends as far as the hinged end of board 2. Near the free end of the board 2 is an eye 8 carrying hook 9 engageable with eye 10 on leg 4 of this assembly when leg 4 strikes against the depending portion of angle 15. In this hooked position, the leg assembly is positioned so that its cross member 23 is at a greater horizontal distance from the hinged end of the board than is pin 17. Both angle 11 and angle 15 may, instead of being as shown in the drawing, extend transversely across the boards almost to the lengthwise edges thereof, in this way adding to the non-tipping stability of the board.

The height at which the extended ironing board 1,2 is supported may be adjusted by easing up on bolts 6 in the leg assemblies, permitting the required relative motion of the legs under the influence of the internal spring, and then tightening bolts 6. Each leg assembly may be adjusted to a different height, either to provide a level ironing board when the supporting surface is not level, or to incline the board as the operator may find convenient.

It is to be understood that I have shown but one specific embodiment of my invention and that modifications of details are possible without departing from my invention.

What I claim is:

1. A foldable ironing board composed of two ironing board sections hinged to each other along the opposed transverse edges, means on the lower surface of the board sections for locking the sections to each other when the sections are aligned with each other, a first leg support on the lower surface of one of the board sections, at a minimum distance from the hinged edge of the section, a first leg assembly pivotable in such first support, means for locking the first leg assembly parallel the section, a second leg support on the lower surface of the other of the board sections at a distance from the free edge of that section substantially equal to the distance of the first leg support from the hinged edge of the one

board section, and a second leg assembly pivotable in such second support.

2. A foldable ironing board comprising a first board member, hinging means at an end thereof, a first leg member pivotally supported on the lower surface of the first board member, a first fixed stop for determining a maximum rotation of the first leg member in the direction away from the lower surface of the board member of somewhat more than ninety degrees, a first means for locking the first leg against the first stop when the leg has been rotated to the stop, a second board member attached to the hinging means and rotatable from the position of superimposition on the first board member through 180 degrees to be aligned with the first board member, a second means for locking the first and second board members to each other when so aligned, a second leg member pivotally supported on the lower surface of the second board member, a second removable stop which on removal permits rotation of the second leg member up to approximately ninety degrees from the lower surface of the second board and on replacement with the second leg member rotated therebeyond permits of a counter-rotation of the second leg member to a predetermined degree only, and a third means for locking the second leg member against the replaced second stop.

3. A foldable ironing board in accordance with claim 2 in which each leg member is independently adjustable in length and has means to lock the leg member at the adjusted length.

4. A foldable ironing board comprising two board sections of substantially equal length, a hinged connection therebetween permitting of their relative rotation from being mutually superimposed to being mutually aligned, means operable when the sections are aligned to lock them to each other in such position, a first leg assembly pivotable about a first point on the lower surface of one section from a position parallel the section to a position approximately perpendicular the surface, the first point being at a first distance from the hinged connection so that the leg assembly in its position parallel the section does not extend as far as the hinged connection, a first locking means adaptable to lock the first leg assembly either parallel to the section or in a position somewhat less than perpendicular thereto, the locking means being removable to permit pivoting the first leg assembly in the direction away from the section surface, a second leg assembly pivotable about a second point on the lower surface of the other section from a position parallel the section to a position somewhat beyond the perpendicular to the surface at the second point, the point being at a second distance from the free edge opposite the hinged edge of the said other section substantially equal to the first distance, and a second locking means adaptable to lock the second leg assembly in its pivoted position somewhat beyond said perpendicular to the surface at the second point.

5. A foldable ironing board comprising a hinge, two board sections of substantially equal length connected to each other by the hinge and adapted to be folded upon each other in overlapping relation when not in ironing use with the surfaces of the sections on which the ironing is done when in ironing use juxtaposed in overlapping relation, a supporting leg pivotally attached to each section and individual thereto, one of the supporting legs being pivotally attached near the hinged edge of one section and the other of the

supporting legs being pivotally attached near the free edge of the other section, the length of each leg being such that when it occupies a position substantially parallel its section its free end does not extend beyond the section, the one section and each supporting leg being rotatable only about the hinge, respectively, in relation to the pivotally attached section, in the same direction to a maximum position which is the position in use for ironing, and individual means for locking the board section and each leg in its respective maximum rotated position.

6. A foldable ironing board comprising two ironing board sections of substantially equal length hinged to each other along the mutually opposed transverse edge of each, means on the lower surface of the board sections for locking the sections to each other when the sections are aligned with each other, a first leg support on the lower surface of one of the board sections at a minimum distance from the hinged edge of the one section, a first leg assembly pivotable in the first support, means for locking the first leg assembly parallel the one section, a second leg sup-

port on the lower surface of the other board section at a distance from the free edge of that section substantially equal to the distance of the first leg support from the hinged edge of the one section, a second leg assembly pivotable in the second support, the one section being swingable about the other section only in the direction which is the same as the direction in which each leg assembly is swingable in relation to the respective sections when opening the board for ironing use and when collapsing the board for storage.
